of New York

Application November 9, 1946, Serial No. 134,654

Term of patent 7 years

(Cl. D86—10)

To all whom it may concern:

Be it known that I, Ladislas Medgyes, a citizen of Hungary, resident of New York city, in the county of New York and State of New York, have invented a new, original, and ornamental Design for a Combined Lipstick and Vanity Case, of which the following is a specification, reference being had to the accompanying drawing, forming part thereof.

In the drawing:

Fig. 1 is a front elevational view of the combined lipstick and vanity case showing my new design;

Fig. 2 is a side elevational view of the same; and

Fig. 3 is a top plan view.

The side not shown is substantially plain.

I claim:

The ornamental design for a combined lipstick and vanity case, as shown and described.
LADISLAS MEDGYES.
